MULTIPLE POCKET FOR GARMENTS

George H. Lester, Birmingham, Ala.

Application August 11, 1941, Serial No. 406,412

3 Claims. (Cl. 2—253)

This invention relates to a multiple pocket construction for garments, particularly for the bibs of overalls, and has for an object the provision of such a pocket construction which shall be simple of design and easy to assemble, and which shall combine strength of design with ready accessibility to the pockets.

A further object of my invention is to provide an overall bib pocket combination which shall include a relatively large rear pocket extending substantially across the bib and a plurality of smaller pockets arranged over the relatively large pocket and with overlapping safety openings, together with means to reinforce the pocket construction.

Features of my invention are illustrated in the accompanying drawing forming a part of this application, in which—

Fig. 1 is a front view of an overall bib having my improved pocket construction applied thereto;

Fig. 2 is a sectional view taken along the line II—II of Fig. 1;

Fig. 3 is a side view looking in the direction of the arrows III—III of Fig. 1; and

Fig. 4 is a sectional view taken along the line IV—IV of Fig. 1.

Referring to the drawing, I show a bib 10 of a suit of overalls having my improved pocket construction applied to the front thereof. The pocket combination is composed of a plurality of layers of fabric, the inner layer 11 being constituted by the body of the garment. The next or intermediate layer of fabric 12 is joined to the body 11 of the garment in a manner to be described later, around the entire periphery of the pocket combination, except on the right hand side of the wearer, where it is joined from the bottom up to a line of reinforcing stitching 13, the remainder being unstitched to provide an opening 14 into the pocket from the right hand side of the wearer, which opening may be closed by a snap fastener 16. The construction so far described provides a relatively large pocket, readily accessible to the wearer from the right hand side of the wearer, and which is secured all around to the body of the garment except for the lateral opening.

Immediately above the intermediate layer 12 is provided a central outer layer 17 which is joined, intermediate its sides, to the intermediate layer 12 by parallel vertical rows of stitching 18 and 19 so spaced as to form a relatively narrow scabbard pocket 21 which may be employed for holding a pencil 22. A lower opening 23 in the

scabbard pocket 21 provides for accommodating a short pencil or tool, while an upper opening 24 adapts the pocket for a longer pencil or tool.

On the opposite sides of the pocket combination 5 are provided lateral, outer fabric layers 26 and 27, both of which overlap the outer edges of the central outer layer 17. The layer 27 is joined to the intermediate layer 12 and to the body of the garment 11 along the left hand side of the wearer by 10 means of parallel rows of stitching 28, which extend from top to bottom and around the entire pocket construction, joining all layers together, except for the opening 14 already described. Vertical rows of stitching 29 join the left hand outer 15 layer 27 to the central outer layer 17 from the bottom up to a reinforcing stitching 31, where the rows 29 stop to leave an opening 32 with the edge of the layer 27 overlapping the edge of the layer 17 to provide a safety pocket 33. It will be noted 20 that the pocket 33 extends from the outer left boundary of the combination pocket, on the left of the wearer, to the parallel rows of stitching 18 and 19 defining the scabbard pocket 21.

To the right of the wearer, a similar pocket 34 25 is formed by the outer layer 26 which is stitched to the central outer layer 17 by rows of stitching 36 up to a reinforcing stitching 37, where the stitching stops to leave an opening 38 overlapped by the edge of the outer layer 26. It will be noted, 30 by reference to Fig. 3, that the outer layer 26 is joined to the intermediate layer 12 and to the body 11 of the garment by a continuation of the double rows of stitching 28, which extend around the bottom of all the pockets and up to the reinforcing stitching 13 already described. From the reinforcing stitching 13 up to the top of the opening 14 for the large pocket first described, the outer layer 26 is joined only to the intermediate layer 12. The pocket 34 just described, as will be seen by reference to Fig. 2, extends from the vertical row of stitching 18 to the outer boundary of the pocket construction and thus provides a safety pocket similar to pocket 33 for such articles as watches, purses, etc.

45 In order to provide additional strength for the entire construction, a reinforcing band of fabric 39 extends across the entire upper end of the pockets and the bib 10, and is joined thereto by parallel rows of stitching 41 and 42. A button hole 43 may be provided through this band and through the body of the garment to accommodate the upper end of a watch chain, not shown.

From the foregoing it will be apparent that I have devised an improved multiple pocket construction for garments of the character de-

scribed, which is strong and sturdy, with readily accessible multiple pockets, and providing adequate safety features to prevent the loss of articles therefrom.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. A multiple pocket for garments of the character described including a plurality of layers of fabric, the rear layer being comprised by the body of the garment, the intermediate layer adjacent the body of the garment being relatively wide and joined to the body of the garment at the top, bottom, along one side, and part way up from the bottom of the opposite side to form a relatively wide rear pocket opening from the side, a fastener for the side opening of said pocket, a central outer layer of fabric, a central scabbard pocket formed by parallel vertical rows of stitching joining the central outer layer to the intermediate layer, lateral outer layers of fabric on each side of the intermediate layer and overlapping the central outer layer along the outer vertical edges of the latter and cooperating with the central outer layer and the intermediate layer to form oppositely disposed front side pockets with central openings and safety overlapping edges, and rows of stitching joining the outer edges of the outer layers of fabric through the intermediate layer to the body of the garment except for the lateral opening of the rear pocket where the cooperating lateral outer layer is joined only to the intermediate layer.

2. A multiple pocket for garments of the character described including a plurality of layers of

fabric, the rear layer being comprised by the body of the garment, the intermediate layer adjacent the body of the garment being relatively wide and joined to the body of the garment at the top, bottom, along one side, and part way up from the bottom of the opposite side to form a relatively wide rear pocket opening from the side, a snap fastener for the side opening of said pocket, a central outer layer of fabric, a central scabbard pocket formed by parallel vertical rows of stitching joining the central outer layer to the intermediate layer, lateral outer layers of fabric on each side of the intermediate layer and overlapping the central outer layer along the outer vertical edges of the latter and cooperating with the central outer layer and the intermediate layer to form oppositely disposed front side pockets with lateral openings and safety overlapping edges, rows of stitching joining the outer edges of the outer layers of fabric through the intermediate layer to the body of the garment except for the lateral opening of the rear pocket where the cooperating lateral outer layer is joined to the intermediate layer, and a fabric reinforcing strip stitched across the upper ends of the pockets joining all the layers to the body of the garment.

3. A multiple pocket for overalls comprising a relatively large inner pocket opening from the side and formed by fabric joined to the body of the garment across the front, a snap closure for the opening, similar outer side pockets and a central scabbard pocket formed by a piece of fabric secured to and over the inner pocket by parallel vertical rows of stitching and lateral pieces of fabric secured to and over the sides of the inner pocket by rows of stitching to form overlapping central safety openings for the side pockets, and a reinforcing strip secured across the top of the several pockets and to the body of the garment.

GEORGE H. LESTER.
